UNITED STATES PATENT OFFICE.

RUDOLF LOEB, OF JENKINTOWN, PENNSYLVANIA.

FABRIC-HOLDING MEANS FOR OVEREDGE SEWING-MACHINES.

1,260,923.

Specification of Letters Patent. Patented Mar. 26, 1918.

Application filed September 30, 1916. Serial No. 123,078.

To all whom it may concern:

Be it known that I, RUDOLF LOEB, a citizen of the United States, and a resident of Jenkintown, Montgomery county, Pennsylvania, have invented certain Improvements in Fabric-Holding Means for Over-edge Sewing-Machines, of which the following is a specification.

My invention relates to sewing machines of the overedge or overlock stitch type; such for instance as the structure illustrated in my application for patent filed March 25, 1915, Serial No. 16,899; and the object of my present invention is to equip a machine of this character with means whereby circular sections of fabric may have the ornamental overedge or overlock stitching forming the subject of my Patent No. 1,162,498, dated November 30, 1915, applied to the edge of the same, which sections of fabric, under the operation of such machine, are maintained truly circular.

The stitching operation referred to is identical or substantially so with the operation proposed to be carried out by use of the structure of my pending application and disclosed in my prior patent before referred to, but the stitches are applied at a point radially disposed with respect to the axis of a circular piece of fabric which is rotated during the stitching operation so that the ornamental stitched edge applied to the same will be truly circular.

These and other features of my invention are more fully described hereinafter, reference being had to the accompanying drawings, in which:

Figure 1, is a plan view of the improved machine having the equipment forming the subject of my present invention.

Fig. 2, is a front elevation of the same.

Fig. 3, is an end elevation.

Fig. 4, is a sectional view on the line IV—IV, Fig. 1, and

Fig. 5, is a view illustrating a circular piece of fabric with its edge provided with ornamental stitches.

The purpose and function of my present invention is to apply the stitches made in accordance with the arrangement of the structure shown in my pending application, which stitches increase and decrease in length in regular order, such increase and decrease being carried on automatically and continuously whereby a scalloped edge is

formed of what may be termed overedge or overlock stitches, to the edge of a circular piece of fabric, and so that such embroidered or stitched edge will be truly circular.

As in the machine of my pending application before referred to, I provide a movable wedge-shaped member 1 over which the short and long stitches constituting the improved embroidered edge are formed, which member is moved at regular intervals with respect to the point at which the stitches are laid, with the result that short stitches will be formed over the point of the member when moved in one direction; such stitches gradually lengthening to the full sized 60 stitches formed over the main body or heel of such stitch member and gradually shortening as the stitch member is moved in the opposite direction. The tapered or pointed member 1 over which the stitches are formed 65 is reciprocated back and forth with respect to the point at which the stitches are laid, as set forth in said pending application, but as my present invention relates to means for taking care of the circular piece of fabric so 70 that such stitches may be applied to the edge of the same as it is rotated; description of the operation of such stitching means is not thought to be necessary.

This stitching operation is identical with 85 that proposed in my pending application and forming the subject of my prior patent, and the object of my present invention is to support a circular section of fabric with its 90 edge in position to receive the short and long 95 stitches laid by the stitching mechanism in order that the ornamental stitching can be applied to the edge of the circular piece of fabric. To this end, the bed-plate of the machine is provided with an extension table 10, which may be at the left-hand side of the same, which table may be circular if desired, and may be held to the bed-plate by screws 11. It is recessed at the center as indicated at 12, to receive a rotatable plate 13; 100 a central ball forming a bearing for the plate plate 13 being indicated at 14, and said plate 13 is recessed at 15 adjacent its outer edge for the reception of a friction producing ring 16 of rubber or equivalent material. 105

The circular piece of cloth to be stitched is laid on top of the table 10 over its rotatable central section or plate 13 and held by a clamping or pressure disk 17 under the tension of a spring 18. The disk 17 is car- 110

ried by a spider frame which may comprise a plate 19 and posts 20 connecting the same with the disk 17. The plate 19 is rotatable in a bearing formed by an upper plate 21 having a downwardly depending stem 22 which passes through the plate 19 of the spider support for the clamping disk and through a ring 23 below the same; the parts so assembled being connected together by a 10 nut 24. By preference, balls 25 are interposed between the plate 19 and the plate 21 and ring 23 so as to facilitate movement of the clamping disk and its spider frame with respect to its support.

15 The plate 21 is provided with an upwardly extending hollow stem 26 receiving the spring 18, and this stem is vertically movable in the hub 27 of a bracket 28 suitably secured to the bed-plate of the machine. 20 The spring is confined in the socket of the stem 26 by an arm 29, which may be secured to the bracket by a screw 30. To raise the pressure disk 17 against the tension of the spring 18, a suitable lever 31 is provided, 25 pivoted to the bracket at 32 and adapted to engage a pin 33 on the stem 26; the hub 27 being slotted at 34 to permit movement of said pin.

In operation, the attendant raises the 30 clamping disk 17, slips a section of material in place, guiding it by hand until it is centered with respect to the axis of the plate 13 rotatable in the table, and then drops the clamping disk 17 into engagement with said 35 movable plate 13. The stitching operation is then commenced, and the normal feed of the fabric which accompanies such stitching operation effects rotation of the fabric holding means and fabric, and the stitching operation proceeds until the entire edge of the 40 circular section of fabric has been covered with the ornamental stitches. When one section is finished, the clamping disk is relaxed and a fresh section is put in place.

45 The table receiving the circular section of material may be of any convenient size, and for operating upon different sized sections of material, the only thing necessary is to provide the axis of rotation of the plate 13 and pressure disk 17 at a proper distance 50 from the point where the stitching operation takes place with reference to the size of the circular pieces of material.

While I have referred to the formation of 55 a special type of ornamental stitch at the edge of the circular piece of fabric, it will be understood that my improved means for effecting the stitching of the edges of circular pieces of fabric may be applied to 60 other forms of overedging machines.

I claim:

1. In a sewing machine, the combination 65 with stitch-forming mechanism and fabric-feeding mechanism, of a table, a rotatable member mounted in said table at one side

of the stitch-forming mechanism, said rotatable member being adapted to receive a circular section of fabric disposed with its edge in position to be engaged by the stitch-forming mechanism, and means for clamping 70 said fabric to the rotatable member; said fabric being moved with the rotatable member by the engagement of said fabric-feeding mechanism with the fabric during the formation of the stitches. 75

2. In a sewing machine, the combination 80 with stitch-forming mechanism and fabric-feeding mechanism, of a table, a rotatable member mounted in said table at one side of the stitch-forming mechanism, said rotatable member being adapted to receive a circular section of fabric disposed with its edge in position to be engaged by the stitch-forming mechanism, a rotatable clamping member axially mounted over said rotatable 85 member, and means for lowering said clamping member to hold the fabric to the rotatable member; said fabric being moved with the rotatable member by the engagement of said fabric-feeding mechanism with the 90 fabric during the formation of the stitches.

3. In a sewing machine, the combination 95 with stitch-forming mechanism and fabric-feeding mechanism, of a table carried by the bed-plate of the machine, a circular member rotatably mounted in said table at one side of the stitch-forming mechanism; said table being recessed to receive said circular member and the latter being adapted to receive a circular section of fabric disposed with its edge in position to be engaged by said stitch-forming mechanism, and means for clamping 100 said fabric to the rotatable member; said fabric being moved with the rotatable member by the engagement of said fabric-feeding mechanism with the 105 fabric during the formation of the stitches.

4. In a sewing machine, the combination 110 with stitch-forming mechanism and fabric-feeding mechanism, of a table carried by the bed-plate of the machine, a circular member rotatably mounted in said table at one side of the stitch-forming mechanism; said table being recessed to receive said circular member 115 and the latter being adapted to receive a circular section of fabric disposed with its edge in position to be engaged by said stitch-forming mechanism, a rotatable clamping member axially mounted over said rotatable member, means for lowering said clamping member to hold the fabric to the rotatable member, and means for raising and holding 120 said clamping member in the elevated position; said fabric being moved with the rotatable member by the engagement of said fabric-feeding mechanism with the fabric 125 during the formation of the stitches.

5. In a sewing machine, the combination 130 with stitch-forming mechanism and fabric-

feeding mechanism, of an extension table carried by the bed-plate of the machine, a circular plate rotatably mounted in said table, a central bearing for said plate, the latter having friction material in its upper surface, a rotatable clamping member disposed axially with respect to said rotatable plate, means for holding said clamping plate in engagement with a section of fabric overlying the friction material of the rotatable plate, an antifriction bearing for said clamping plate, and means for lifting said clamping plate and holding the same in the elevated position; the rotatable plate and clamping plate holding the fabric thereto moving automatically with the fabric as sitches are applied to the edge of the latter.

6. In a sewing machine, the combination with stitch forming mechanism and fabric-feeding mechanism, of an extension table carried by the bed-plate of the machine, a circular plate rotatably mounted in said table, a central bearing for said plate, the latter having friction material in its upper surface, a rotatable clamping member disposed axially with respect to said rotatable plate, means for holding said clamping plate in engagement with a section of fabric overlying the friction material of the rotatable plate and positioned to be engaged by said stitch-forming mechanism, a ball bearing mount for said clamping plate, and means for lifting said clamping plate; the rotatable plate and clamping plate moving automatically with the fabric as the edge of the latter is stitched.

7. In a sewing machine, the combination with stitch forming mechanism and fabric-feeding mechanism, of an extension table carried by the bed-plate of the machine, a circular plate rotatably mounted in said table, a central ball support for said plate, said plate having friction material annularly disposed in its upper surface, a rotatable clamping member disposed axially with respect to said rotatable plate, a bracket for supporting said clamping member, means for holding said clamping plate in engagement with the friction material of the rotatable plate, and a lever carried by the bracket for lifting said clamping plate; the

rotatable plate and clamping plate moving automatically with the fabric as the edge of the latter is stitched.

8. In a sewing machine, the combination with stitch forming mechanism and fabric-feeding mechanism, of an extension table carried by the bed-plate of the machine, a circular plate rotatably mounted in said table, a central ball support for said plate, said plate having friction material annularly disposed in its upper surface and adapted to receive a circular section of fabric with its edge in position to be engaged by the stitch forming mechanism, a rotatable clamping member disposed axially with respect to said rotatable plate to hold the fabric in place, a bracket for supporting said clamping member, a spring for holding said clamping plate in engagement with a section of fabric overlying the friction material of the rotatable plate, and a lever carried by the bracket for lifting said clamping plate; the rotatable plate and clamping plate moving automatically with the fabric as the edge of the latter is stitched.

9. In a sewing machine, the combination with stitch-forming mechanism and fabric-feeding mechanism, of a rotatable clamping means located at one side of such stitch-forming mechanism for holding a circular section of fabric disposed with its edge in position to be engaged by said stitch-forming mechanism; said fabric being moved with said rotatable holding means by the engagement of said fabric-feeding mechanism with the fabric during the formation of the stitches.

10. In a sewing machine, the combination with stitch-forming mechanism and fabric-feeding mechanism, of a table carried by the bed-plate of the machine and located at one side of the stitch-forming mechanism, and rotatable clamping means disposed above said table for holding a circular section of fabric disposed with its edge in position to be engaged by said stitch-forming mechanism; said fabric being moved with the rotatable clamping means by the engagement of said fabric-feeding mechanism with the fabric during the formation of the stitches.

RUDOLF LOEB.
